UNITED STATES PATENT OFFICE.

JAMES STEWART, OF PITTSBURG, PENNSYLVANIA.

SHOULDER-BRACE AND SKIRT-SUPPORTER.

SPECIFICATION forming part of Letters Patent No. 373,699, dated November 22, 1887.

Application filed October 3, 1887. Serial No. 251,278. (No model.)

To all whom it may concern:

Be it known that I, JAMES STEWART, of Pittsburgh, in the county of Allegheny and State of Pennsylvania, have invented a new and useful Improvement in Shoulder-Braces and Skirt-Supporters; and I do hereby declare the following to be a full, clear, and exact description thereof.

My invention relates to an improvement in shoulder-braces and skirt-supporters; and it consists in the construction and arrangement of devices which I will now proceed to describe, reference being had to the accompanying drawings, forming part of this specification, in which—

Figure 1 is a plan view of my improved device. Fig. 2 is a view showing the same as applied to the body.

Like letters of reference indicate like parts in each.

In the drawings, *a a* represent two shoulder-loops formed of textile fabric or any other suitable material. Extending between these loops, and sewed or otherwise secured to the same, is a back strap, *b*, composed of an elastic fabric of woven cloth and rubber or other suitable material. Extending from the lower portions of the loops *a a*, and sewed or otherwise fastened thereto, are short bands or strips *c c* of cloth or other textile fabric, to the ends of which are secured the buckles *d d*. Engaging with the teeth of the buckles are bands or strips *e e*, which are suitably sewed or secured to bridle-strips *f f*, the ends of which bridle-strips are sewed or otherwise fastened to a belt, *g*, at one end of which is a buckle, *h*, the belt being provided with buttons *i*, for the purpose of securing the skirts of the wearer to the belt.

The operation is as follows: In adjusting and placing my improved shoulder-brace and skirt-supporter to the body the arms are passed

through the shoulder-loops *a a*, as shown in Fig. 2, and the belt *g* is then fastened around the waist. Owing to the buckles *d*, the distance between the belt *g* and the shoulder-loops *a* may be easily regulated. By means of the elastic back-band *b* a pressure is exerted on the shoulders through the loops *a*, tending to keep the shoulders of the wearer drawn back in their proper position, while at the same time the elasticity of the band permits of an easy and free movement of the shoulders.

I am aware that shoulder-braces and skirt-supporters are not new; and I do not desire to claim the same, broadly. The advantages of my improvement are, however, the lightness and simplicity of the device, which may be worn without discomfort, and is equally effective as the more complicated, heavy, and cumbersome devices heretofore in use. It may be easily adjusted so as to suit and fit people of different sizes, without trouble, by merely lengthening or shortening the strips *e* in the buckles *d*.

My improved device may be easily adapted for gentlemen's wear with but slight modifications.

Having thus described my improvement, what I claim, and desire to secure by Letters Patent, is—

In a shoulder-brace and skirt-supporter, the combination of the shoulder-loops *a*, elastic band *b*, buckles *d*, bridle-straps *e f*, and the belt *g*, substantially as and for the purposes described.

In testimony whereof I have hereunto set my hand this 26th day of September, A. D. 1887.

JAMES STEWART.
